UNITED STATES PATENT OFFICE.

CONRAD REGENBOGEN, OF KIEL, GERMANY, ASSIGNOR TO FRIED. KRUPP AKTIEN-
GESELLSCHAFT GERMANIAWERFT.

FUEL-INJECTOR.

1,142,623.

Specification of Letters Patent. Patented June 8, 1915.

Application filed June 10, 1912. Serial No. 702,840.

To all whom it may concern:

Be it known that I, CONRAD REGENBOGEN, a citizen of the German Empire, residing at Kiel, Germany, have invented certain new 5 and useful Improvements in Fuel-Injectors, of which the following is a specification.

For the reliable operation of a fuel injector valve fed with fuel of low combustibility, for example, tar oil, it is essential that with 10 reduced loads upon the machine, in which the fuel pump advances small quantities of fuel toward the nozzle, some fuel must always be present in the annular space surrounding the seat of the needle, at the time 15 of opening the fuel needle, since otherwise, when the needle is opened, cold pressure air will enter the cylinder in advance of the admission of the newly presented fuel, which would hinder development of the conditions 20 of ignition.

The present invention has for its object to provide a fuel injecting device which is so arranged that it will insure certain ignition even with reduced loads upon the machine.

25 In the accompanying drawing is shown an embodiment of the invention by way of example.

Figure 1 shows in section a fuel injector device, and Fig. 2 a special arrangement of 30 the regulating device.

The arrangement of the particular fuel injector valve is known and consists essentially in a valve attachment A, the fuel needle B, the atomizing plates C and the atomizing cone D. The fuel is fed through a channel E, and the pressure air through a channel F. In accordance with the present invention, the annular space G lying immediately above the seat of the needle B, is 35 connected with a space of low pressure, for example, with the outer atmosphere, through a channel H in which is located a cut-off slide J. This slide J is so controlled from a shaft K (for example the governor shaft) 40 through the medium of a cam disk L, L¹, that, at the end of the advancement of fuel by the fuel pump, and before the opening of the fuel needle B, it is opened for a brief time (at the time-period indicated on the drawing) and then immediately closes again. This temporary opening of the channel H produces in the nozzle, under the influence of the injector pressure air, a movement of the contents of the nozzle toward 45 the annular space G. If the annular space 50 55 60 65 70 75 80 85 90 95 100 105 110

G, in consequence of a light load upon the machine, has been blown completely free of fuel, the pressure air which would be present in the space G at this time, can be dissipated through the channel H, and with the properly measured opening duration and opening capacity of the channel H, it can be replaced by fuel newly advanced through the atomizing plates C and the cone D, which fuel, after closure of the channel H and at the opening of the fuel needle, will be the first to reach the cylinder and will thus effect ignition with certainty.

Since with heavy loads upon the machine, such an exhaust of air from the annular space G is not necessary, for the reason that the nozzle will not be blasted free of fuel, the control of the cut-off slide J will be suitably arranged in such a manner that the channel H will be opened only by an effort to transmit a predetermined load. Moreover, for the sake of economy in pressure air, the arrangement of the control can be so determined that the channel will first open but very slightly with heavy loads on the engine and that the opening capacity or opening duration of the channel H gradually increases, attaining the highest extent when running light. This can be effected, with the described control, for example, by having the cam L¹ designed as a cam, with variable lift, and having the cam-disk L so displaced, by the governor, on the shaft K, that the controller roll, runs upon the cylindrical portion of the cam-disk during the greatest loads, and with decreasing loads, gradually runs over upon the steeply ascending portions of the cam. An arrangement of this kind is represented in Fig. 2, showing the position of a cam disk L² (corresponding to the cam disk L in Fig. 1) when the machine is running light and requires therefore the maximum opening capacity and maximum opening duration of the slide J. The sleeve m¹ of the governor M will then occupy its highest position.

If the load upon the machine increases, the sleeve m¹ will descend, and, by means of the rod gear N O P displace the cam disk L² to the left. By this movement, on account of the cam L³ with variable lift, the opening capacity and the opening duration of the slide J will continually decrease according to the increasing load upon the machine, until, when the machine is under full

load, the controller roll will coöperate with the cylindrical part of the cam disk L², in which latter position the slide J remains at rest.

5 Since the carrying off of some of the fuel, at the opening of the channel H, cannot always be prevented, provision must be made for returning it again to the fuel container.

Naturally, the control of the channel H 10 can be effected in any desired manner instead of through the cam disk.

I claim:—

1. In a valved fuel-injecting device for internal combustion engines operating with 15 fuels of low combustibility; and having a needle valve, and a housing therefor with a chamber immediately behind the point of said needle valve; means through which said chamber can be brought momentarily into 20 communication with a space having less pressure at that moment, previous to opening the needle valve.

2. In a valved fuel-injecting device for internal combustion engines operating with 25 fuels of low combustibility; and having a needle valve, and a housing therefor with a chamber immediately behind the point of said needle valve; means through which said chamber can be brought into communication 30 with a space of less pressure, previous to opening the needle valve, said means comprising a channel leading from said valve chamber to atmosphere and means for opening and closing said channel.

3. In a valved fuel-injecting device for internal combustion engines operating with 35 fuels of low combustibility; and having a needle valve, and a housing therefor with a chamber immediately behind the point of 40 said needle valve; means through which said chamber can be brought into communication with a space of less pressure, previous to opening the needle valve, said means comprising a channel leading from said valve

chamber to atmosphere and means for opening and closing said channel, said opening and closing means being automatically regulated to commence opening only after the load upon the engine falls below a predetermined measure. 45

4. In a valved fuel-injecting device for internal combustion engines operating with fuels of low combustibility; and having a needle valve, and a housing therefor with a chamber immediately behind the point of 50 said needle valve; means through which said chamber can be brought into communication with a space of less pressure, previous to opening the needle valve, said means comprising a channel leading from said valve 55 chamber to atmosphere, means for opening and closing said channel and means for timing and graduating the action of said opening and closing means.

5. In a valved fuel-injecting device for 60 internal combustion engines operating with fuels of low combustibility; and having a needle valve, and a housing therefor with a chamber immediately behind the point of 65 said needle valve; means through which said chamber can be brought into communication with a space of less pressure, previous to opening the needle valve, said means comprising a channel leading from said valve 70 chamber to atmosphere, means for opening and closing said channel and means for timing and graduating the action of said opening and closing means, said timing and graduating means being regulated to vary the 75 area of the opening capacity of the channel 80 closure, inversely as the load imposed upon the engine.

In testimony whereof I have affixed my signature in presence of two witnesses.

CONRAD REGENBOGEN.
